METHOD OF AND APPARATUS FOR STARTING AND SUSTAINING OPERATION OF AN EXPLOSIVE-ENGINE.

1,282,655.

Specification of Letters Patent. Patented Oct. 22, 1918.

Original application filed October 13, 1915, Serial No. 55,661. Divided and this application filed December 4, 1916. Serial No. 134,965.

To all whom it may concern:

Be it known that I, FRED WALLACE THURSTON, a citizen of the United States, residing at San Francisco, in the county of San Francisco and State of California, have invented new and useful Improvements in Methods of and Apparatus for Starting and Sustaining Operation of an Explosive-Engine, of which the following is a specification.

10 This invention relates to an improved method of and apparatus for starting an explosive engine without priming, this application being a divisional application with respect to my application filed October 13, 15 1915, Serial No. 55,661, for improvement in vaporizers.

It is a feature of this invention to collect the condensate in the manifold when the engine cools off, and retain this collected 20 condensate, in such a manner as to enrich the initial thin restarting mixture. By enriching this thin initial restarting mixture, I am able to obtain a sufficient number of 25 initial or starting explosions in the engine to not only partially warm up the same, but also, to supply a certain requisite initial volume of exhaust gases from the cylinders, which exhaust gases are utilized as a heating medium. Subsequent to the actual starting 30 of the engine, it is important to supply the cylinders with a dry combustible mixture so that the operation of the engine can be continued.

Now in the use of distillate or other low 35 grade hydrocarbons, it is not only difficult to get a dry mixture from any ordinary carburetor but it is even difficult to get, especially at the starting period, an efficient pick-up of the fuel to even impregnate the air 40 sufficiently to make an operative explosive mixture. When using distillate, that mixture, following the first initial thin inrushing air, is heavily ladened with globules and mist of liquid particles which would ob- 45 jectionably carbonize the interior portions of the engine if admitted thereto.

Now therefore it is an object of this invention not only to enrich the first thin restarting air but it is also an object to vaporize the subsequent fuel liquid ladened air in such a manner as to supply the engine with a dry combustible gas, and support the igni-

tion, by such a mixture as will cause the engine to continue to operate after it has been started.

55

Therefore, after the first thin inrushing mixture has been enriched by the collected and retained condensate, I apply the heat from the exhaust gases, resulting from the initial explosions, in such a way as to break up the fuel particles and vaporize the subsequent mixture following the first thin inrushing mixture.

In the accompanying drawing I will more particularly describe the manner in which 65 the improved method is carried out and in the appended claims I will particularly point out the novelty of the invention.

As illustrated, 1 designates, as a whole, 70 an intake manifold for a four cylinder explosive engine and it will be observed that the manifold is constructed to drain into an attaching terminal end 2, to which is attached a device for carrying out my improved method.

75

This device includes an outer shell 3 having inlet and outlet pipes 4 and 5 for passage through the outer shell of a heating medium consisting of the exhaust gases from the engine. The outer shell 3, has an inner 80 shell 6, preferably cylindrical, which functions as a primary heating surface, and between which inner shell and outer shell the exhaust gases pass. I reduce the inner shell 6, as indicated at 7, and thread on to the reduced end 7, a cap 8, to which the terminal 85

2 may be secured by its flange 9, in any desired manner. The reduced end 7 forms an outlet 10 which is preferably equal in diameter to the terminal 2. The bottom of the shell 3 is recessed at 11 to receive a deflector 12 which preferably extends transversely across the path of the supplied mixture. The outer margin of the deflector 12 is interposed between shell 3 and a fitting 13, the latter being coupled at 14, to a pipe 15, leading from a suitable means of supply of the fuel mixture, such as the carburetor. The deflector 12 is provided with a series of openings 16, which are preferably laterally disposed, radially with respect to the bore 17, so that the incoming fuel will be deflected outwardly, radially, against the inner face 18, of the shell 6. For this purpose, the fitting 90

95

90

95

100

100

13 is flared at 19 to provide passage for a suitable volume of the mixture.

I preferably mount upon the deflector 12, an obconic screen 20, having its lower margin 21 spaced a considerable distance from the shell 6, and its upper margin 22, disposed closely adjacent shell 6. The top of the screen 20 is open, as indicated at 23, the opening 23 being preferably equal in diameter to the outlet bore 10. Thus it will be seen that the screen 20 is interposed in the path of the mixture in such a manner that all of the mixture leaving shell 6 is suction drawn by the engine through said screen.

15 After an explosive engine has been brought to a position of rest subsequent to operation, the gas or fuel in the intake or manifold condenses, after the parts cool, and this leaves the walls of the intake coated 20 with a sweat or covering of globules of liquid fuel. This liquid condensate very efficiently and quickly impregnates air or a thin mixture to form a rich explosive vapor. Now this condensation drains down 25 the intake, and because of the fact that the screen collector is interposed in its path of this condensation, and because of the mesh openings of this collector are too small for the condensate to pass therethrough, I have 30 found that after the engine has cooled off, and in taking out the screen 20, that the latter is coated and dampened with this condensate.

Now in re-starting an engine, especially 35 when using a low-grade hydro-carbon, but even in the case of gasoline, the first inrush or influx of air fails to pick up a sufficient amount of the liquid fuel so as to enter the cylinder as a rich vapor, and therefore in 40 most cases it is necessary to prime, in one manner or another. However, with my improved device, the first influx of restarting thin mixture is so rich, by passage through the film coated collector, that it is not necessary to prime the engine because the first 45 influx mixture is sufficiently rich to make effective explosions.

Immediately after these initial explosions have been obtained, the exhaust gases are applied as a heating medium to heat up the 50 shell 6 and the screen so that the mixture immediately following the initial or starting mixture, and which is heavily laden with fuel particles in liquid form, will be under 55 the action of heat so that it will be transformed into a dry vapor when it enters the engine.

Thus after I first obtain the initial explosion, the next step is to so treat the following mixture that the operation of the engine will be sustained until the engine becomes heated to such an extent that it will operate in good working form.

It will be understood that in the employment of my improved method, the engine

will not be under load, as the primary purpose of this novel method is to get the engine under operation in the total absence of any load.

An additional advantage results from the 70 fact that I not only start the engine without priming but I am able to start the engine and avoid the admission thereto of a mixture which is heavily laden with fuel particles, and which invariably increases 75 carbonization.

The interdependence between the method 80 step of collecting and retaining the condensate in the path of the thin inrushing mixture, on the one hand, and the subsequent step of immediately after initial explosion, 85 of applying heat so that the subsequent or following mixture will be vaporized, should now be perfectly clear. However, I consider it novel, as a method, to first collect 90 and then retain the condensate in the path of the first thin inrushing mixture irrespective as to how the following mixture is treated.

It is believed that the novelty and utility 95 of my improved method will be fully understood from the foregoing description, and while I have herein shown and described apparatus for carrying out my improved method, it will be understood that I do not 100 wish to be limited to this apparatus as the invention resides in the method and I therefore do not wish to be limited at all except for such limitations as the claims may import.

I claim:

1. An improved method of starting and sustaining operation of an explosive engine, which consists, in collecting fuel condensate formed in the cooled engine and retaining 105 the same in the path of the thin restarting influx to enrich the latter sufficiently to obtain starting explosions, and in applying the exhaust gases from such initial explosions to heat the mixture following the thin starting 110 influx to sustain operation of the engine after the same has been started, substantially as described.

2. An improved method of starting and sustaining operation of an explosive engine, 115 which consists, in collecting fuel condensate formed in the cooled engine and retaining the same in the path of the thin starting influx to enrich the latter sufficiently to obtain starting explosions, and in applying heat to 120 the liquid fuel laden mixture following the thin starting influx to thereby sustain operation of the engine after the same has been started, substantially as described.

3. As an improved method of starting an 125 explosive engine, which consists, in collecting and retaining fuel condensate formed in the cooled engine intake, and in forcing the usual thin restarting influx against such collected fuel condensate to enrich such initial 130

influx prior to its admission to the engine, substantially as described.

4. An improved method of starting and sustaining operation of an explosive engine, which consists, in collecting fuel condensate formed in a cooled engine by a fine mesh screen positioned to cause the condensate to drain directly onto and progressively film over the interstices of the screen by gravity and in the path of the thin restarting influx to enrich the latter sufficiently to obtain starting explosions, and in applying the exhaust gases from such initial explosions to heat the richer mixture following the thin starting influx to thereby sustain operation of the engine after the same has been started, substantially as described.

5. In a device for vaporizing fuel, a screen collector, means for heating the fuel before the latter is drawn through said screen collector, said collector being disposed in the path of the fuel so that the condensate formed in the engine intake may be deposited on the collector thereby enriching the restarting initial influx, substantially as described.

6. As an improved means for restarting an explosive engine, a screen collector disposed in the path of drain of the fuel condensate from the engine intake to collect and retain such condensate for enrichment of the initial thin restarting mixture, and means for utilizing the initial restarting exhaust from the explosions of such enriched thin mixture to heat said collector and vaporize the richer mixture immediately following said initial thin re-starting mixture, substantially as described.

7. As an improved means for restarting an explosive engine, a screen collector disposed substantially edgewise in the path of drain of the fuel condensate from the engine intake to collect and retain such condensate for enrichment of the initial thin restarting mixture, and means for applying the heat

of the initial restarting exhaust from the explosions of such enriched thin mixture to heat said collector and vaporize the richer mixture immediately following said initial thin restarting mixture, substantially as described.

8. As an improved means for restarting an explosive engine, a screen collector disposed in the path of drain of the fuel condensate from the engine intake to collect and retain such condensate for enrichment of the initial thin restarting mixture, a screen heating member along side of said screen, and means for applying the heat of the initial restarting exhaust from the explosions of such enriched thin mixture to said heater to heat said collector and vaporize the richer mixture immediately following said initial thin restarting mixture, substantially as described.

9. As an improved means for restarting an explosive engine, a screen collector disposed substantially edgewise in the path of drain of the fuel condensate from the engine intake to collect and retain such condensate for enrichment of the initial thin restarting mixture, a screen heating member disposed along side of said screen, and means for applying the initial restarting exhaust from explosions of such enriched thin mixture to said heating member to heat said collector and vaporize the richer mixture immediately following said initial thin restarting mixture, substantially as described.

10. In a device for gasifying fuel, a screen collector, means for heating the fuel drawn through said screen collector, said collector being disposed in the path of the fuel so that the condensate formed in the engine intake may be deposited on the collector thereby enriching the restarting initial influx, substantially as described.

In testimony that I claim the foregoing as my own, I hereby affix my signature.

FRED WALLACE THURSTON
